INVENTOR
THOMAS HOWARD SCOTT

BY

Munn & Co

ATTORNEY

UNITED STATES PATENT OFFICE.

THOMAS HOWARD SCOTT, OF COATESVILLE, PENNSYLVANIA.

SHUTTLE.

Application filed July 31, 1923. Serial No. 654,867.

To all whom it may concern:

Be it known that I, THOMAS HOWARD SCOTT, a citizen of the United States, and a resident of Coatesville, in the county of Chester and State of Pennsylvania, have invented a new and Improved Shuttle, of which the following is a full, clear, and exact description.

This invention has relation to shuttles 10 designed for silk weaving machines and contemplates more particularly an improvement in the tensioning means thereof.

At the present time in the common construction of shuttles thread guides are 15 formed by straight pins set in the shuttle body, which pins are usually embodied in the shuttle by drilling holes in the shuttle body part way through the same, fitting the pins in the holes and then filling in the 20 exposed ends of the holes to cover the outer ends of the pins with wax or any other suitable plastic material. In time the pins become worn by the thread and to remove and reinsert them in changed position, or to 25 substitute new pins for the worn ones requires the services of a skilled mechanic. Furthermore the pins placed in the old way work loose and cause in many instance serious damage or imperfection in the goods being 30 woven.

It is therefore the principal object of the present invention to provide an improved means for mounting the guide pins of the tension device within the shuttle body, in 35 order to effectually retain said pins against accidental displacement, in order to facilitate either removal and reinsertion in a changed position, or the substitution of new pins for the worn ones.

As a further object the invention contemplates a guide pin mounting for the tension means of a weaving shuttle which is comparatively simple in its construction, inexpensive to manufacture and which is 45 thoroughly reliable and highly efficient in its purpose.

With the above recited and other objects in view, the invention resides in the novel construction set forth in the following 50 specification, particularly pointed out in the appended claims and illustrated in the accompanying drawings, it being understood that the right is reserved to embodiments other than those actually illustrated herein 55 to the full extent indicated by the general

meaning of the terms in which the claims are expressed.

In the drawings—

Figure 1 is a side view of a shuttle equipped with a thread guide pin mounting 60 constructed in accordance with the invention.

Fig. 2 is an enlarged fragmentary plan view thereof, the same being illustrated in section approximately on the line indicated 65 at 2—2 in Fig. 1.

Fig. 3 is a transverse sectional view taken approximately on the line 3—3 of Fig. 2.

Referring to the drawings by characters of reference, A designates the shuttle body, 70 B and C the communicating recesses extending through the opposite sides of the shuttle body and within which the tension means is mounted. A movable thread guide consisting of a lever D having a plurality 75 of spaced eyes E is mounted in the recess B for swinging movement, the said lever being provided at its pivoted end with a bearing eye F and an actuating arm G which extends into the recess C and is connected by means of a tension element H to a pin I for normally swinging the lever 80 D in one direction. The stationary thread guiding means which consists of a plurality of pins J is in the present instance mounted 85 in the recess B by means of a substantially U-shaped mounting member 10 which consists of parallel upper and lower walls 11 and 12 connected by a bight or inner side wall 13. The upper and lower 90 walls 11 and 12 are provided with aligned apertures 14 and 15 for the reception of the guide pins J, the latter openings 15 being closed at their outer or lower ends by a flange 16 which is the reversely bent outer 95 extremity of the lower wall 12. The bight or inner side wall 13 extends only from the forward end of the mounting member 10 to a point medially of its length and is provided with an opening 17 which receives an 100 attaching screw 18 anchored in the bottom wall of the recess B. The lower wall 12 projects at its rear end an appropriate distance beyond the rear end of the upper wall 11 and is suitably apertured to receive 105 therethrough the transverse screw 19 which extends through one side wall of the recess B and is anchored in the opposite side wall to constitute together with the screw 18 a 110 means for retaining the mounting member

means for retaining the mounting member 110

10 in place against movement and at the same time a bearing pin for the bearing eye F of the lever D. After the stationary 5 guide pins J are inserted in the aligned openings 14 and 15 in the mounting member 10 the lower ends of the pins will rest upon the flange 16 and when the mounting member is inserted in the recess B as illustrated 10 in Figs. 1 and 2, the extremities of the pins J which lie in the openings 14 in the upper wall 11 will be retained against accidental movement due to the fact that the upper wall of the recess B closes the outer ends of the openings 14. The screw 18 is then 15 passed through the opening 17 in the bight or inner side wall 13 and anchored in the inner side wall of the recess B. The lever D is then inserted through the recess C into the recess B after which the screw 18 is inserted through the upper side wall of the 20 recess B through the bearing eye F, the apertured rear extremity of the lower wall 12 of the mounting member and finally threadedly anchored in the lower wall of the recess B. Under this construction and arrangement it will thus be apparent that the stationary thread guiding pins J are effectually mounted and retained within the recess B of the shuttle against accidental 25 displacement or movement which would tend to cause serious damage or imperfection in the goods to be woven. It will be further apparent that the mounting member readily admits of removal of the pins for reinserting 30 the same in changed position or for the substitution of new pins for the worn ones. The mounting member 10 is preferably stamped from a single sheet of material which is then bent upon itself to the proper 35 form for the completed device.

I claim:

1. In a weaving shuttle, including a body having a recess for the accommodation of the tension device, means for mounting the stationary guide pins of the tension device in the recess in said shuttle body, comprising a removable mounting member having spaced connected apertured walls within 45 which the opposite ends of said guide pins are received, and means on one of the walls of the mounting member for covering the outer ends of the apertures therein to provide a stop for preventing displacement of the guide pins therethrough. 50

2. In a weaving shuttle, including a body having a recess for the accommodation of the tension device, means for mounting the stationary guide pins of the tension device in the recess in said shuttle body, comprising a removable mounting member having spaced connected apertured walls within which the opposite ends of said guide pins are received, and means on one of the walls of the mounting member for covering the outer ends of the apertures therein to provide a stop for preventing displacement of the guide pins therethrough, the walls of the recess abutting the outer side of the opposite wall of the mounting member serving to cover the outer end of the apertures 60 therein to prevent displacement of the guide pins therethrough when the mounting member is positioned in the recess. 65

3. In combination with a weaving shuttle including a body having a recessed portion for accommodating the tension device, of means for mounting the stationary guide pins of the tension device in said recessed portion, comprising a mounting member of substantially U-shape in cross section and including spaced side walls having apertures therein for receiving the opposite ends of the guide pins, the connecting wall between the side walls receiving therethrough the anchoring means for retaining the mounting member within the recess, a flange on one of the side walls of the mounting member bent outwardly and parallel to the side wall to overlie and close the outer end of the apertures therein, one of said side walls being extended beyond the other and provided with an aperture for receiving therethrough the fulcrum upon which the movable guide element of the tension device is mounted. 70 75 80 85 90

THOMAS HOWARD SCOTT.
